FASTENER

Edward A. Otto, Chicago, Ill., assignor to Western Electric Company, Incorporated, New York, N. Y., a corporation of New York

Application October 12, 1932, Serial No. 637,416

9 Claims. (Cl. 179—91)

This invention relates to fasteners and more particularly to improvements in mounting devices to facilitate the fastening of key frame assemblies in key shelves.

5 A common type of fastener which has been used for key frame assemblies is illustrated in Craft Patent No. 1,050,520, January 14, 1913. This type of fastener requires a pair of spaced rails at each side of the shelf opening, a stud 10 being provided at each end of the key frame assembly which extends between the rails and which is secured by a screw and washer bearing against the inner edges of the rails.

An object of the invention is to provide a fastener which firmly secures a part in position by engagement with only one abutment or rail on the supporting framework.

In accordance with the object of the invention, one embodiment contemplates a key frame assembly similar to that shown in the Craft patent 15 and having studs at the ends thereof, the outer ends of the studs being internally threaded to receive screws which serve to force washers against the inner edges of fixed rails, one at each 20 side of the opening in a shelf assembly and thus force the ends of the metallic frame against the outer edges of the frame. One end of each washer rests against the rail while the other has an element extending toward the frame, which may 25 or may not be integral therewith and which serves as a second rail.

Other objects and advantages will be apparent from the following detailed description taken in conjunction with the accompanying drawing, 30 wherein

Fig. 1 is a vertical sectional view of a key shelf showing a key frame assembly and one embodiment of the fastening means in elevation;

Fig. 2 is an enlarged fragmentary sectional 40 view of the fastening means shown in Fig. 1;

Fig. 3 is a vertical sectional view taken along the line 3—3 of Fig. 2; and

Figs. 4, 5, 6 and 7 are fragmentary and partially 45 sectional views of other embodiments of the invention.

Referring now to the drawing, wherein like reference numerals designate similar parts throughout the various views, numeral 10 designates a key shelf having spaced members 11 and 12 braced 50 by a bar 13 extending horizontally therebeneath and secured thereto by any suitable means, such as screws. Metallic rails 15 and 16 are secured to the inner walls of the members 11 and 12 of the key shelf 10 by any suitable means, such as 55 screws, and have their lower edges positioned

adjacent the bar 13. The rails 15 and 16 may be of stock material of a desired width, which is less than the thickness of the shelf members 11 and 12, allowing a space between the upper edges of the rails and the upper edges of the shelf members for ends 17 and 18 of a key frame 19 and ends of a cover 20. The key frame 19 has integral reinforcing ribs 21 terminating short of the ends thereof. In all of the embodiments of the invention illustrated, except that of Fig. 7, 5 adjacent the ends of the frame 19 are fastening studs 22 rigidly secured to the frame and extending at right angles with respect thereto, the ends of the studs farthest from the frame being internally threaded to receive screws 23.

The embodiment of the invention shown in Figs. 1 to 3, inclusive, comprises a fastening member 25 having a horizontally extending elongated rail engaging portion 26 apertured to receive the threaded portion of the screw 23, the head of the 20 latter abutting the lower surface of the fastening member when in assembled position. In this embodiment of the invention, a lug 27 is formed integral with the elongated portion 26 and extends to and in engagement with the end of the 25 frame, as shown in Figs. 1 and 2.

Extending through apertures in the cover 20 are key levers 30 which are pivotally mounted in the frame 19 and arranged to actuate switches 31, the latter being carried by switch frames 32 30 mounted upon and suspended from the frame 19.

The unit, which consists of the frame 19, the cover 20, and the other members carried thereby, may be referred to hereinafter as the key frame assembly. In mounting the key frame assembly 35 in the key shelf, the fastening members are moved to positions so that the portions 26 of the fastening member 25 will be in parallel relation with the rails 15 and 16. While in this position, the key frame assembly is disposed in the position 40 shown in Fig. 1 so that the ends of the frame 19 will rest upon the rails 15 and 16 and the upper surface of the cover 20 will be flush with the upper surface of the shelf members 11 and 12 of the key shelf 10. The fastening members are then 45 moved through an arc of approximately 90° so that they will be in the positions shown in Fig. 1. The screws 23 are then rotated to force the outer ends of the portions 26 in intimate engagement 50 with the lower surfaces of the rails 15 and 16, the force upon the inner portions of the members 26 being transmitted to the lugs 27, which are held against longitudinal movement by the ends of the frame 19. In this manner the lugs 27 serve as an 55

additional rail for supporting one end of each of the fastening members 26.

The embodiment of the invention shown in Fig. 4 is the same in construction as that shown in Figs. 1 to 3, inclusive, with the exception of the upper portion of the lug 27, which extends outwardly, as indicated at 35, parallel with the portion 26. The outwardly extending portion 35 of the lug 27 has an aperture 36 therein slightly larger than the stud 26 so as to receive the stud and permit free movement thereof relative to the stud. In this embodiment of the invention the fastening member 25 may be swung through an arc to permit the key frame assembly to be inserted in place in the key shelf 10 and upon the rails 15 and 16 and then moved into the position shown in Fig. 4, after which the screw 23 may be tightened, forcing the portion 26 of the fastening member 25 into intimate engagement with the lower surface of the adjacent rails 15 or 16 and forcing the frame 19 in intimate engagement with the upper surface of the rails. When force is applied to the portion 26, the end thereof in engagement with the rail is held against further movement, whereas additional force by the screw 23 tends to move the opposite end thereof, that is the end integral with the lug 27, upwardly and toward the rail, but this end is limited in this movement by the portion 35 of the lug 27 abutting the stud 22.

The embodiment of the invention shown in Fig. 5 differs from the embodiment shown in Fig. 1 only in the fastening or rail engaging member and the lug, the construction of the other members of the key frame assembly and the construction of the key shelf being the same. In this embodiment of the invention the fastening member and the lug are separate, the fastening member being in the form of an elongated washer 40 apertured to receive the threaded portion of screw 23 and arranged to have one end engage the rail 15 or 16, and the other end engaging the lower extremity of the lug, which in this embodiment is indicated at 41. The lug 41 is in the form of a casting having an upper leg 42 and a lower leg 43 extending in opposite directions from an apertured central portion 44, which portion extends around the stud 22 and has flattened surfaces 45 positioned adjacent the rail 15 or 16 so as to prevent rotation of the lug.

The fastening member or washer 40 may be rotated upon the screw 23 a sufficient distance to allow the key frame assembly to be inserted in place in the key shelf 10, after which the fastening member is moved into position, as shown in Fig. 5, and then forced into intimate engagement with the lower surface of the rail and the lower leg 43 by tightening the screw 23, the washer having been turned through 90° so as to engage the rail 15 and the lug 41. The lug 41 serves as a second rail and is held upon the stud 22 by the fastening member 40.

The embodiment of the invention shown in Fig. 6 is similar to that shown in Fig. 5, the only difference lying in the construction of the lug. In this embodiment the lug, indicated at 50, is formed of stock material of rectangular cross-section and apertured as at 51 to receive the stud 22. The lug 50 has a flat end 52 which abuts the end of the frame 19 and a tapered riding surface 53 which is arranged to be engaged by the fastening member 40. With this type of lug the fastening member 40 may be swung through an arc to allow the key frame assembly to be disposed in place upon the rails 15 and 16, after which

the fastening member may be moved upon the riding surface 53 and about the screw 23 so that it will engage the rail 15 or 16 and the lowest edge of the lug 50. The purpose of tapering the lower end of the lug 50 is to provide a clamping gap to permit the fastening member 40 to effectively engage the rail and the lowermost end of the lug. By tightening the screw 23 the fastening member 40 is forced into intimate engagement with the lower surface of the rail and the lower surface of the lug securing the key ring assembly in place.

The embodiment of the invention shown in Fig. 7 is somewhat similar to that shown in Fig. 6 with the exception that one member in Fig. 7 takes the place of two members in Fig. 6. This member may be termed a stud 60 having any desired cross-sectional contour, preferably of hexagonal contour, so that it may be easily manufactured in an automatic screw machine. The stud 60 has an integral lug 61 which is upset in a countersunk opening 62 in the frame 19 so as to rigidly secure the stud to the frame. The lower end of the stud 60 has a tapered riding surface 63 and a flat abutting surface 64, the tapered surface 63 serving to aid a fastening member 65 in being moved upon the abutting surface 64. The fastening member 65 is elongated and is carried by a screw 66, similar to the screw 23 in the other figures, which extends through an aperture in the fastening member and is receivable in the thread opening 67 in the stud 60. In view of the fact that the fastening member 65 is elongated instead of round in general contour, it may be rotated upon the screw 66 so as to permit the key frame assembly to be disposed in the key shelf 10 without removing the screw and the fastening member. After the key assembly has been disposed in place upon the rails 15 and 16, the fastening member may be swung through an arc to position one end of the fastening member in engagement with the rail 15 while the other end engages the abutting surface of the stud 60, and then, by tightening the screw 66, the key frame assembly will be rigidly secured in place.

Although this invention has been described herein in connection with a telephone switchboard, it will be understood that the invention is capable of other applications and is only limited by the scope of the appended claims.

What is claimed is:

1. A fastener for switchboard keys or the like, comprising a stud carried by a key, a fixed rail for supporting the key, a fastening member having one end arranged to engage said rail, a lug positioned between the other end of said fastening member and the key for limiting the movement of the fastening member, and means carried by said stud for moving said fastening member and said key into intimate engagement with said rail.

2. A fastener for switchboard keys or the like, comprising a stud carried by a key, a fixed rail for supporting the key, an elongated fastening member having one end arranged to be rotated into and out of engagement with said rail, a lug positioned between the end of said fastening member and the key for limiting the movement of the fastening member, and means carried by said stud for moving said fastening member and said key into intimate engagement with said rail.

3. A fastener for switchboard keys or the like, comprising a stud carried by a key, a fixed rail for supporting the key, an elongated fastening member having one end arranged to engage said

5 rail, a lug integral with the other end of said fastening member and extending toward the key for limiting the movement of the fastening member, and means carried by said stud for moving said fastening member and said lug for fastening said key to said rail.

10 4. A fastener for switchboard keys or the like, comprising a stud carried by a key, a rail for supporting the key, a fastening member having one end arranged to engage said rail, a lug integral with the other end of said fastening member and extending toward and arranged to engage the key, and means carried by said stud and extending through said fastening member for moving 15 said fastening member and the key into intimate engagement with the rail.

20 5. A fastening member for switchboard keys or the like, comprising a stud carried by a key, a fixed rail for supporting the key, a fastening member having one end arranged to engage said rail, a lug integral with the other end of said fastening member and having a transversely extending portion apertured to receive said stud, and means carried by said stud for moving said 25 fastening member and said key into intimate engagement with said rail, said lug and its association with said stud limiting the movement of the fastening member.

30 6. A fastener for switchboard keys or the like, comprising a stud carried by a key, a fixed rail for supporting the key, a lug mounted upon said stud and having one end arranged to engage the key and the other end positioned substantially parallel with one surface of the rail, a fastening member arranged to be moved into intimate engagement with said rail and adjacent end of said lug, and means carried by said stud while moving said fastening member into intimate en-

gagement with said rail and with said lug for securing said key to said rail.

7. A fastener for switchboard keys or the like, comprising a stud carried by a key, a fixed rail for supporting the key, a lug apertured to receive the stud and having one end disposed in engagement with the key while the other end is tapered, a fastening member arranged to engage said rail and the tapered end of said lug, the tapered end of said lug facilitating the movement of said fastening member into and out of engagement with said rail, and means carried by said stud for moving said fastening member into intimate engagement with said rail and with said stud for securing the key in place.

15 8. A fastening member for switchboard keys or the like, comprising a stud carried by a key and having an abutting surface, a fixed rail for supporting the key, an elongated fastening member arranged to be moved into and out of general 20 alignment with said rail and the abutting surface of said stud, and means carried by said stud for moving said fastening member into intimate engagement with said rail and said abutting surface when positioned in general alignment there- 25 with for forcing said key in intimate engagement with said rail.

25 9. A fastener for switchboard keys or the like, comprising a fixed rail for supporting a key, an elongated fastening member having one end ar- 30 ranged to be rotated into and out of engagement with said rail, a lug positioned between the other end of said fastening member and a key for lim- 35 iting the movement of the fastening member toward the key, and means carried by the key for moving said fastening member and said key into intimate engagement with said rail.

EDWARD A. OTTO.
